UNITED STATES PATENT OFFICE.

GRINROD KERSHAW, OF ROCKDALE, ENGLAND.

CREEL FOR USE WITH WARPING AND BEAMING MACHINES AND THE LIKE OR FOR
USE WITH LOOMS FOR WEAVING OR OTHER MACHINES.

Application filed April 22, 1925, Serial No. 24,976, and in Great Britain April 28, 1924.

This invention of improvements in creels for holding bodies of yarn relates to creels for use with warping and beaming machines or the like, for example section warping and beaming machines or for use with looms for weaving or other machines in order to supply yarn drawn off or unwound from yarn bodies, such for example as bobbins, cones, cheeses or other bodies holding or formed of yarn to be led to beams or the like or to looms or other machines directly or through reeds, hecks or other means for determining or regulating the extent of and closer or more open distribution of yarn in passage.

The present invention consists in creels in which stationary frames are provided to support the thread guides or tension devices and thread guides in fixed positions for yarns to be led from them to beams or to looms or other machines directly or through reeds, hecks or other means for determining or regulating the extent of and closer or more open distribution of yarns and in which the places of support for the yarn bodies are provided in fixed positions in or on frames which are situate between the stationary frames supporting the thread guides or tension devices and thread guides and are movable wholly or in sections as whole frames without change in the relative position of their parts and the positions of the places of support for the holders or bodies of yarn thereon nearer to and further from the thread guides or tension devices and thread guides.

Creels constructed according to this invention are advantageous in comparison with creels of equal capacity having the thread guides or thread guides and tension devices carried by frames movable as whole frames or in sectional portions away from and towards stationary supports for yarn bodies and creels comprising movable frames in which pegs or holders disposed in pairs to be turned about in that they require less space for installation and attendants and involve less spreading of the places from which yarns converge and less obtuse or abrupt convergence of the yarn at the sides and consequently allow of more equal drag or tension on all the yarns while allowing as easy or easier access to the places of support for yarn holders or bodies of yarn for

the application of yarn bodies and the tying of yarns. Further in comparison with creels in which yarn body supports have been mounted in oppositely directed pairs extending from a common support movable either simply about an axis in relation to a stationary support carrying movable thread guides and tensioning devices or about an axis and laterally relatively to a stationary support carrying thread guides and tensioning devices in fixed positions, creels provided according to this invention present the advantage either of requiring less space for installation and working or greater simplicity and convenience in the application of yarn bodies to be unwound.

Further in comparison with creels provided with thread guides and tension devices which being placed in one position at a little distance from the yarn bodies while yarns or threads are being unwound from yarn bodies and into another position closer to or between or among the yarn bodies for the application of fresh yarn bodies in position to be unwound, creels provided according to this invention are advantageous in minimizing the opportunities for the entanglement of yarns or threads from neighboring yarn bodies.

The accompanying drawings show an illustrative example of a creel provided according to this invention. Figs. 1 and 2 are respectively a side elevation and a plan of a creel applied for use with a beaming frame and shown broken to shorten the figures. Fig. 3 is a transverse section taken on the plane indicated by the lines 3—3 of Figs. 1 and 2.

The same numerals of reference indicate corresponding parts in all the figures.

In the drawings 4 is a stationary frame supporting thread guides 5 and tension devices 6 on its outer sides 7, 8 and 9 is a frame providing the places of support 10 for holders or bodies of yarn and movable nearer to and further from the thread guides 5 and tension devices 6.

In the stationary frame 4 in the case illustrated upright bars 7, 8 of channel form are secured as by bolts to brackets 11 to be secured to the floor on which the creel is to stand and are formed with lugs 12 in which are inserted and secured as by set screws round rods 13 extending along the creel on

the two outer faces 7, 8 and supporting the guides 5 and tension devices 6 for yarn.

The tension devices 6 mounted on the rods 13 may be of any kind suitable and as shown 5 are of the well known form in which a lower disc with a sleeve is mounted to be revolved about a pivot and furnished with a downwardly pressing disc placed around the sleeve so that yarn being passed between the 10 discs is subject to drag or tension thereby while revolving them. The guides 5 for yarn may be of any kind suitable and are shown as of the form described in the complete specification of application for British Letters 15 Patent No. 17,473, of 1911, and presenting overlapping fingers extending over gaps between them and forming guide eyes. For each yarn to be guided there are provided two of the guides 5 and a tension device 6 20 and the two guides 5 and the tension device 6 are so provided are mounted on a block secured by a set screw in an appropriate position on one of the rods 13. The brackets 11 are provided with ribs 14 and the channel bars 7, 8 are made to embrace those ribs 25 14 so as to be in rigid connection with the brackets 11. Longitudinal channel bars 15 are applied with the flanges downwards on the upper ends of the upright bars 7, 8 and 30 are secured to them for example, by bolts and junction brackets or gussets. The longitudinal bars 15 extend each in one length or connected lengths along the upper part of each side of the creel and at convenient 35 intervals support cross channel bars 16 bolted to them with the flanges upward and extending a little beyond the longitudinal bars 15 at each side of the creel. To the upright bars 7, 8 at one end of the creel are 40 fixed arms 17 extending transversely outwards from the creel and formed or provided with guide eyes for yarn. There is one arm 17 for the series of tension devices 6 and thread guides 5 on each rod 13 and 45 in that arm 17 a hole 18 for each of the threads led from each of such tension devices 6 and the thread guides 5 used with it. In the case illustrated the yarns led through 50 the arms 17 are shown as led to a beaming frame 19 indicated diagrammatically. The channel bars 16 form tracks for supporting and guiding rollers 20. Each cross bar 16 supports a roller 20 mounted on a shaft 21 in bearings in two T plates 22 and also a 55 roller 23 provided with a shaft 24 mounted in bearings in such T plates 22. The T plates 22 which are supported by the shafts 21, and 24 are formed with channels 25 and made each to present its channel 25 towards 60 the other and are bolted to an upright bar 26

26 are bolted longitudinal bars 10 of rectangular section and to the others, in the case illustrated three, are bolted angle bars 101. The bars 10 and angle bars 101 extend each in one length or more along the creel 70 and provide places of attachment for pegs 28 on which holders or bodies of yarn to be unwound may be placed.

The T plates 22, the uprights 26, the cross bars 27, the longitudinal bars 10 and the angle bars 101 together form the movable frame. On each bar 10 and angle bar 101 are provided as many pegs 28 as there are tension devices 6 and pairs of thread guides 5 on the rod 13 opposite to such bar 10 or angle bar 101. The short cross bars 27 are so formed that the outer faces of the bars 10 and angle bars 101 are so inclined that, when the movable frame is as shown in Fig. 2 midway between the two sides 7, 8 of the 80 stationary frame 4 and the thread guides 5 and tension devices 6 are duly adjusted in position the axial lines of the pegs 28 secured in them are directed towards the corresponding thread guides 5 and tension devices 6 on the rods 13.

The angle bars 101 are provided in order that the frame 9 may be stiffer than it would if only flat bars 10 were employed in it. The shaft 21 on which the rollers 20 are mounted 95 extends in one length or more along the creel and one end is provided with a chain wheel 29 engaging a chain passed around another chain wheel which is fast with a hand wheel 30 and with it is mounted to be turned upon a stud 31 secured in one end of the frame 9.

By the hand wheel 30 being turned and made to revolve the rollers 20 the movable frame 9 can be moved laterally between the two sides of the stationary frame 4 from 105 the middle position in which it is indicated in Fig. 2 towards either side and back again to the middle. By the movable frame 9 being moved nearer to one side of the stationary frame 4 more space is left 110 between the movable frame 9 and the other side of the stationary frame 4 for the entrance of an attendant to place bobbins, cheeses or other bodies for holding or formed of yarn on the pegs 28 on the one side of the movable frame 9 and by the movable frame 9 being moved correspondingly in the opposite direction more space is afforded 115 for access to the other side of the movable frame 9.

From a bobbin or body holding or formed of yarn applied to one of the pegs 28 yarn is led through the guides 5 and tension device 6 towards which that peg 28 is directed and thence to the guide arms 17 and in the 120

wards the pegs nearest the other end are supplied in order corresponding to their positions.

When the pegs 28 on both sides of the movable frame 9 have been supplied with yarn bodies it is easy by turning the hand wheel 30 to bring the movable frame 9 again into the mid position between the two sides of the stationary frame 4 for yarn to be unwound in the ordinary way.

Ordinarily when the pegs 28 have been once supplied with holders or bodies of yarn the unwinding of yarn from the holders or bodies is stopped before the yarn on or in the holders or bodies has been wholly unwound and full or fresh holders or bodies of yarn to replace them are applied to the pegs 28 and the yarns detached from the holders or bodies removed are attached to the yarns on the full or fresh holders or bodies.

The space necessary for the application of fresh or full bodies for run off or empty ones and the tying of the ends of yarn is obviously very conveniently obtained by the frame 9 being moved first in one direction then in the other.

Yarn bodies or holders of yarn of any kind may be applied to the pegs 28. For example Fig. 3 shows cone shaped bobbins or bodies 32 of yarn applied at one side of the movable frame 9 and cylindrical bobbins or bodies 33 of yarn applied at the other side one cone shaped bobbin 32 and one cylindrical bobbin 33 being shown and Fig. 2 shows conical yarn bodies applied on both sides of the frame 9, and in each case the yarns are shown as being unwound from the ends of the yarn bodies. Instead of pegs any other means for holding the yarn bodies may be provided, and the pegs or other means for holding yarn bodies may be contrived to hold the yarn bodies for yarn to be unwound from the ends or at the sides of the yarn bodies as may be desirable in different cases.

In the drawing the movable frame 9 is shown made in one length so as to be moved in one piece but, in a long creel, a movable frame may be made in two or more sections each similar and movable similarly to the movable frame 9 illustrated.

In like manner the stationary frame 4 may be made in two or more similar sections. Further if desirable, in any case the stationary frame 4 may be constructed so that its sides are inclined one to the other in plan and the movable frame 9 in one section or more may be made with its sides correspondingly inclined one to the other in plan.

In the drawing the movable frame 9 is shown as made to travel by means of rollers on supporting rails and of construction found advantageous but in different cases

different constructions may be of any convenient construction in the parts for supporting yarn bodies and may be made movable in any convenient way for example on slides or otherwise and either simply by attendants pushing or pulling on them or racks and pinions or chains and sprocket wheels working by means of racks and pinions or screws or worm wheels or ropes and pulleys or other means may be provided for enabling attendants to move them from time to time.

The thread guides and tension devices used in creels provided according to this invention may be of any suitable kinds.

Similarly stationary frames may be of any convenient construction providing support for the thread guides or tension devices and thread guides.

Creels provided according to this invention while affording space for the replacement of empty or run off yarn bodies by full or fresh ones conveniently to be accomplished enable the yarn bodies to be unwound to be placed close to the guides 5 to 9 which yarn is led from them so that yarns can be unwound from the ends or from the sides of such yarn bodies without ballooning or swinging excessively outwards or laterally.

What I do claim as my invention and desire to secure by Letters Patent is:—

1. In a creel for receiving yarn bodies and presenting them in positions for yarns to be drawn from them and led to respective places, a stationary frame comprising upright and longitudinal bars in two ranks spaced apart and respectively presenting outer faces forming the outer faces of the creel, cross bars supported on the longitudinal bars to extend from rank to rank to support and to allow movement of a movable frame, rods extending along the outer faces of the creel and carried on said upright bars for supporting thread guides, thread guides mounted on such rods for guiding yarns from yarn bodies to their respective places of passage from the creel, a movable frame comprising plates with bearings for shafts, a shaft extending through said plates and mounted turnably in bearings therein, short shafts severally mounted turnably in bearings of the plates, rollers fixed on said shaft extending through said plates to bear on said cross bars thereby to partake in supporting said plates and in turning of said shaft to move said plates along said cross bars, rollers fixed on said short shafts to bear on said cross bars and thereby with the rollers on said shaft extending through the plates to support said plates, means for revolving the shaft extending through said plates, uprights supported by said plates and longitudinal bars carried by said uprights to carry yarn body supports and yarn body supports on

the longitudinal bars on said uprights, whereby turning of said shaft extending through said plates in one direction or the other will move the movable frame and yarn body supports towards or away from said thread guides.

2. In a creel for receiving yarn bodies and presenting them in positions for yarns to be drawn from them and led to respective places, a stationary frame comprising upright and longitudinal bars in two ranks spaced apart and respectively presenting outer faces forming the outer faces of the creel, cross bars supported on the longitudinal bars to extend from rank to rank to support and to allow movement of a movable frame, rods extending along the outer faces of the creel and carried on said upright bars for supporting thread guides and tensioning devices thread guides and tensioning devices mounted on such rods for guiding yarns from yarn bodies to their respective places of passage from the creel, a movable frame comprising plates with bearings for shafts, a shaft extending through said plates and mounted turnably in bearings therein, short shafts severally mounted turnably in bearings of the plates, rollers fixed on said shaft extending through said plates to bear on said cross bars thereby to partake in supporting said plates and in turning of said shaft to move said plates along said cross bars, rollers fixed on said short shafts to bear on said cross bars and thereby, with the rollers on said shaft extending through the plates to support said plates, means for revolving the shaft extending through said plates, uprights supported by said plates and longitudinal bars carried by said uprights to carry yarn body supports and yarn body supports on the longitudinal bars on said uprights, whereby turning of said shaft, extending through said plates in one direction or the other will move the movable frame and yarn body supports towards or away from said thread guides and tensioning devices.

3. In a creel for receiving yarn bodies and presenting them in positions for yarns to be drawn from them and led to respective places, a stationary frame for supporting thread guides, comprising two stationary structures fixed in position with space between them and presenting corresponding inwardly directed faces to one another and supporting and guiding means extending parallel one to another between said stationary structures for supporting a movable frame and guiding it parallel to itself, thread guides mounted on said stationary structures for guiding yarns from yarn bodies to their respective places of passage from the creel, a movable frame which is supported on said supporting means and guided parallel to itself thereby and extends lengthwise between the stationary structures of

said stationary frame, presents longitudinal faces fixed in definite and constant relative position and respectively parallel to the inwardly directed faces of said stationary structures and is movable nearer to and further away from said stationary structures only in its totality parallel to itself and yarn body supports on said movable frame for receiving and holding yarn bodies, movement of said movable frame as a whole parallel to itself enabling said yarn body supports to be moved towards and away from the thread guides.

4. In a creel for receiving yarn bodies and presenting them in positions for yarns to be drawn from them and led to respective places, a stationary frame for supporting thread guides and yarn tensioning devices, comprising two stationary structures fixed in position with space between them and presenting corresponding inwardly directed faces to one another and supporting and guiding means extending parallel one to another between said stationary structures for supporting a movable frame and guiding it parallel to itself, thread guides and yarn tensioning devices mounted on said stationary structures for guiding yarns from yarn bodies to their respective places of passage from the creel, a movable frame which is supported on said supporting means and guided parallel to itself thereby and extending lengthwise between the stationary structures of said stationary frame, presents longitudinal faces fixed in definite and constant relative position and respectively parallel to the inwardly directed faces of said stationary structures and is movable nearer to and further away from said stationary structures only in its totality parallel to itself and yarn body supports on said movable frame for receiving and holding yarn bodies, movement of said movable frame as a whole parallel to itself enabling said yarn body supports to be moved towards and away from the thread guides and yarn tensioning devices.

5. In a creel for receiving yarn bodies and presenting them in positions for yarns to be drawn from them and led to respective places, a stationary frame for supporting thread guides, comprising two stationary structures fixed in position with space between them and presenting corresponding inwardly directed faces to one another and presenting rods for supporting thread guides, and supporting and guiding means extending parallel one to another between said stationary structures for supporting a movable frame and guiding it parallel to itself, thread guides mounted on said stationary structures for guiding yarns from yarn bodies to their respective places of passage from the creel, a movable frame which is supported on said supporting means and guided parallel to it-

self thereby comprises bars for supporting yarn body supports, extends lengthwise between the stationary structures of said stationary frame and presenting longitudinal faces fixed in definite and constant relative position and respectively parallel to the inwardly directed faces of said stationary structures and is movable nearer to and further away from said stationary structures only in its totality parallel to itself and yarn body supports on the bars of said movable frame for receiving and holding yarn bodies, movement of said movable frame as a whole parallel to itself enabling said yarn body supports to be moved towards and away from the thread guides.

6. In a creel for receiving yarn bodies and presenting them in positions for yarns to be drawn from them and led to respective places, a stationary frame for supporting thread guides and yarn tensioning devices, comprising two stationary structures fixed in position with space between them and presenting corresponding inwardly directed faces to one another and presenting rods for supporting thread guides and yarn tensioning devices and supporting and guiding means extending parallel one to another between said stationary structures for supporting a movable frame and guiding it parallel to itself, thread guides and yarn tensioning devices mounted on said stationary structures for guiding yarns from yarn bodies to their respective places of passage from the creel, a movable frame which is supported on said supporting means and guided parallel to itself thereby comprises bars for supporting yarn body supports, extends lengthwise between the stationary structures of said stationary frame, presents longitudinal faces fixed in definite and constant relative position and respectively parallel to the inwardly directed faces of said stationary structures and is movable nearer to and further away from said stationary structures only in its totality parallel to itself and yarn body supports on the bars of said movable frame for receiving and holding yarn bodies, movement of said movable frame as a whole parallel to itself enabling said yarn body supports to be moved towards and away from the thread guides and yarn tensioning devices.

7. In a creel for receiving yarn bodies and presenting them in positions for yarns to be drawn from them and led to respective places, a stationary frame for the support of thread guides comprising two stationary structures fixed in position with space between them formed of upright and longitudinal bars, presenting corresponding inwardly directed faces and cross bars supported on the longitudinal bars of said structures to extend parallel one to another from one such structure to the other to sup-

port and to allow movement of a movable frame and to guide it parallel to itself, rods extending along the outwardly directed faces of said stationary structures for supporting thread guides, thread guides mounted on such rods for guiding yarns from yarn bodies to their respective places of passage from the creel, a movable frame which is supported and movable on said cross bars and guided parallel to itself thereby, comprises plates supported by and movable on and guided by said cross bars and supporting uprights and longitudinal bars carried by said uprights to carry yarn body supports and is movable nearer to and further away from said stationary structures only in its totality parallel to itself and yarn body supports on the longitudinal bars on said uprights for receiving and holding yarn bodies, movement of said movable frame as a whole parallel to itself enabling said yarn body supports to be moved towards and away from the thread guides.

8. In a creel for receiving yarn bodies and presenting them in positions for yarns to be drawn from them and led to respective places, a stationary frame for the support of thread guides and yarn tensioning devices comprising two stationary structures fixed in position with space between them formed of upright and longitudinal bars, presenting corresponding inwardly directed faces and cross bars supported on the longitudinal bars of said structures to extend parallel one to another from one such structure to the other to support and to allow movement of a movable frame and to guide it parallel to itself, rods extending along the outwardly directed faces of said stationary structures for supporting thread guides and yarn tensioning devices, thread guides and yarn tensioning devices mounted on such rods for guiding yarns from yarn bodies to their respective places of passage from the creel, a movable frame which is supported and movable on said cross bars and guided parallel to itself thereby, comprises plates supported by and movable on and guided by said cross bars and supporting uprights and longitudinal bars carried by said uprights to carry yarn body supports and is movable nearer to and further away from said stationary structures only in its totality parallel to itself and yarn body supports on the longitudinal bars on said uprights for receiving and holding yarn bodies, movement of said movable frame as a whole parallel to itself enabling said yarn body supports to be moved towards and away from the thread guides and yarn tensioning devices.

9. In a creel for receiving yarn bodies and presenting them in positions for yarns to be drawn from them and led to respective places, a stationary frame for the support of thread guides comprising two stationary

- structures fixed in position with space between them formed of upright and longitudinal bars presenting corresponding inwardly directed faces and cross bars supported on the longitudinal bars of said structures to extend from one such structure to the other to support and to allow movement of a movable frame and to guide it parallel to itself rods extending along the outwardly directed faces of said stationary structures for supporting thread guides, thread guides mounted on such rods for guiding yarns from yarn bodies to their respective places of passage from the creel, a movable frame which is supported on said cross bars and movable on and guided parallel to itself thereby comprises plates supported and movable on and guided by said cross bars and supporting uprights and longitudinal bars carried by said uprights to carry yarn body supports and is movable nearer to and further away from said stationary structures only in its totality parallel to itself and yarn body supports on the longitudinal bars on said uprights for receiving and holding yarn bodies and means for moving said movable frame, movement of said movable frame as a whole parallel to itself enabling said yarn body supports to be moved towards and away from the thread guides.
10. In a creel for receiving yarn bodies and presenting them in positions for yarns to be drawn from them and led to respective places, a stationary frame for the support of thread guides and yarn tensioning devices comprising two stationary structures

fixed in position with space between them formed of upright and longitudinal bars presenting corresponding inwardly directed faces and cross bars supported on the longitudinal bars of said structures to extend from one such structure to the other to support and to allow movement of a movable frame and to guide it parallel to itself, rods extending along the outwardly directed faces of said stationary structures for supporting thread guides and yarn tensioning devices, thread guides and yarn tensioning devices mounted on such rods for guiding yarns from yarn bodies to their respective places of passage from the creel, a movable frame which is supported on said cross bars and movable on and guided parallel to itself thereby comprises plates supported and movable on and guided by said cross bars and supporting uprights and longitudinal bars carried by said uprights to carry yarn body supports and is movable nearer to and further away from said stationary structures only in its totality parallel to itself and yarn body supports on the longitudinal bars on said uprights for receiving and holding yarn bodies and means for moving said movable frame movement of said movable frame as a whole parallel to itself enabling said yarn body supports to be moved towards and away from the thread guides and yarn tensioning devices.

In testimony, that I claim the foregoing as my invention, I have signed my name this 70 seventh day of April 1925.

GRINDROD KERSHAW.
